UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,885, dated November 14, 1893.

Application filed October 7, 1893. Serial No. 487,506. Term of patent 3½ years.

To all whom it may concern:

Be it known that I, CHARLES BOOZE, a citizen of the United States, residing at Buffalo, in the county of Erie and State of New York, **5** have invented and produced a new and original Design for Wall-Paper, of which the following is a specification.

The design consists of a series of wreaths formed of flowers and leaves suspended from **10** ribbon bows and connected by festoons of ribbon and flowers and leaves as represented in the accompanying drawing. The wreaths are placed at uniform distances apart and alternate with the ribbon bows and festoons as **15** shown. In the border or upper portion of the design the wreaths hang from festoons of

flowers and leaves and alternate with small wreaths of flowers and leaves suspended from ribbon bows which unite the ends of the festoons. The small wreaths contain a bow and **20** quiver as shown.

What I claim is—

1. The design for wall paper herein shown and described.
2. In the design for wall paper the border **25** herein shown and described.

Witness my hand this 2d day of October, 1893.

CHARLES BOOZE.
